INVENTOR
HARTWELL F. TUCKER

FIG. 1 is a front perspective view of a pocketed record folder embodying my new design;

FIG. 2 is an inner perspective view thereof as it appears in open position;

FIG. 3 is a rear perspective view of the pocketed record folder as shown in FIG. 1;

FIG. 4 is a top edge view thereof;

FIG. 5 is a right side elevational view of the pocketed record folder as shown in FIG. 1;

FIG. 6 is a fragmentary cross-sectional view in vertical section taken in the plane indicated by the line 6-6 in FIG. 2; and

FIG. 7 is a fragmentary sectional view in vertical section taken in the plane indicated by the line 7-7 in FIG. 2.

The essential features of the design reside in the portions shown in solid lines, particularly the turned-back lip on each strip forming a pocket and the raised riblike projection of a central portion of each pocket-forming strip.

I claim:

The ornamental design for pocketed record folder, as shown and described.
